UNITED STATES PATENT OFFICE.

GARRET SCHENCK, JR., OF MILLINOCKET, MAINE.

APPARATUS FOR DEBARKING LOGS.

987,828.

Specification of Letters Patent. Patented Mar. 28, 1911.

Application filed April 1, 1909. Serial No. 487,172.

To all whom it may concern:

Be it known that I, GARRET SCHENCK, Jr., a citizen of the United States, and resident of Millinocket, in the county of Penobscot 5 and State of Maine, have invented certain new and useful Improvements in Apparatus for Debarking Logs, of which the following is a specification.

My invention relates to debarking or rossing machines, and consists of means whereby to effectually feed the logs past the rossing head while rotating the same, and in features of construction of the parts of the apparatus together with means for discharging 10 the logs automatically after rossing, all as fully set forth hereinafter and as illustrated in the accompanying drawing, in which:

Figure 1 is a side elevation of a debarking 20 machine embodying my improvement; Fig. 2 is a plan view; Fig. 3 is a plan showing one form of rosser head; Fig. 4 a longitudinal section of the body of the rosser head; Fig. 5 an enlarged detached view illustrating 25 one mode of constructing the teeth of the rosser head; Fig. 6 shows a different form of tooth; and Fig. 7 a view illustrating a modification.

The frame A of the apparatus is constructed in any suitable manner to support 30 the necessary parts of the apparatus and has bearings for a series of shafts 2, which are parallel to each other but which are at an angle more or less acute to the side bars of 35 the frame and to the axis of the rossing head hereinafter referred to. Each shaft is provided with a feed roll B and the feed rolls adjacent to the rossing head, that is, those which both precede and succeed the latter, 40 have flanges 3 at the ends adjacent the rossing head, which flanges are preferably flaring or cone-like, as shown, and while the rolls and their flanges may be plain or merely serrated they are preferably provided 45 with lugs or projections 4, which will enable them to take strong hold of the logs which are placed upon them to be fed longitudinally of the frame past the rossing head.

Owing to the inclination of the rolls the 50 logs carried thereby tend not only to travel longitudinally but also to move laterally toward the flanged ends of the rolls and the contact of these flanges with the sides of the logs so acts upon the latter that they are 55 rotated about their longitudinal axes so that in passing the rossing head they are not only

moved longitudinally but rotatively, whereby all portions of the logs are subjected to the rossing action, and this result is insured by providing the projecting lugs upon the 60 feed rolls as before set forth. Those feed rolls which are beyond the rolls which must act upon the log to rotate the same are not provided with flanges but are inclined in the same manner as the first rolls, and in order 65 that the logs may remain upon the latter rolls until they have passed wholly from the flanged rolls, I provide any suitable character of guard or guards which will hold them in place and which may be shifted to 70 permit the rolls to be discharged laterally. This shifting of the guards may be effected automatically through the medium of a contact device J supported by the frame and in position to be struck by the forward end of 75 the log when the latter has traveled sufficiently to be discharged, said contact device being connected with the guards to shift the same. As shown the guards consist of blades D pivoted to one of the side frames of the 80 apparatus and each connected by a link 6 with a bar 7 which is attached at its forward end to the contact device J so that when the latter is swung, by the contact of a log in the direction of its arrow all of the guards 85 will be carried downward and away from the side of the log which will then roll off the feed rolls to any suitable receptacle. A spring 5, after the log passes from the contact device J, restores the latter and the 90 guards to normal position.

The shafts of the feed rolls may be driven in any suitable manner, but as shown are provided with beveled gears for engaging corresponding gears on a driving shaft 8. 95

The rossing head may be constructed in different ways, but as shown there are two heads C upon a single shaft carried by a swinging frame K pivoted at one side of the frame so as to swing to and from the latter 100 to carry the rossing heads to and from the path of the logs, and at the center of the shaft is a belt pulley or cylinder 10 adapted to receive a driving belt by which the rossing head or heads may be rotated. As 105 shown each rossing head has a cylinder with teeth 12 projecting beyond the periphery thereof and so supported that they will yield with a spring action on striking the bark, the result being that a tooth upon first striking the bark is carried in a reverse direction from the rotation of the head, but upon the 110

bark yielding the tooth will spring forward and act percussively on other portions of the bark with a much more effective result than if the tooth was stationary. The teeth may 5 be supported to secure such a spring action in various ways, but as shown the body of the rossing head is a slotted cylinder through the slots of which the teeth may extend and each of which consists of a spring metal, as 10 for instance round spring wire, which is supported by being coiled around a longitudinal bar 13 extending through the cylinder, or is otherwise so held that the projecting toothed end of the strip is maintained with 15 a spring pressure against one end of one of the slots. A simple and effective means of securing this result is to extend the other end of the strip also through one of the slots, or the same slot, and bend it down against the 20 face of the cylinder, as best shown in Fig. 5. The rods 13 may be solid or hollow and extend through bearings in the heads 14 of the cylinder and are held in place by nuts at the end, or otherwise, as may be most desirable. 25 The rossing head instead of being carried by a swinging frame K may be carried by a sliding frame, and any suitable means may be employed for carrying the frame to and from the path of the logs to be operated 30 upon.

While I have shown the feed rolls as provided with flanges or heads 3 forming part of the rolls this is not an absolutely necessary construction as the heads or flanges 35 may be independent of the cylindrical portions of the rolls and may be independently driven, as for instance, as illustrated in Fig. 7 where the cylindrical portion of the roll is secured to the shaft 2, and the head or flange 40 3 turns upon the said shaft and is provided with a gear 22 which may be driven from a suitable spur wheel. In Fig. 6 I have illustrated a somewhat different form of spring tooth where the projecting end is bent back 45 and serrated so as to act with a rasping effect.

The operation of the machine hereinbefore described briefly stated is as follows:— 50 The logs from which it is desired to remove bark are placed upon the feed rolls at the right hand end of the machine, and owing to the inclination of the roll supporting shafts and the arrangement of the teeth on such rolls the log will be fed both longitudinally and toward the side of the machine adjacent which the rossing head is mounted. While all of the rolls B are thus adapted to feed a log both longitudinally and laterally, the rolls immediately adjacent the rossing 55 head are additionally provided with means, such as the toothed flanges 3, by which the log engaged thereby is not only moved longitudinally and laterally as aforesaid, but in addition is rotated so that every portion of the surface thereof is presented to

the rossing head. After passing the rossing head the log is given no further rotary movement and the lateral movement thereof is checked by the upright guards until the longitudinal movement of the log brings it 70 into engagement with the contact device J and causes the latter to move outwardly, thus lowering the guards D and permitting the rolls B to feed the log laterally over the side of the machine. 75

Without limiting myself to the construction shown, I claim:

1. In a debarking machine, the combination with a stationary frame, of a series of rotatable cylindrical parallel toothed rolls, 80 each roll having a flaring toothed flange, the said rolls being arranged and adapted to feed a log both longitudinally of the frame and laterally against said flanges, and said flanges being adapted to rotate the log about 85 its axis, of a rossing device mounted adjacent to the flanged ends of said rolls and adapted to debark the logs as they are transported and turned by the rolls. 90

2. The combination in a debarking machine, of a series of feed rolls adapted to simultaneously feed a log longitudinally and laterally, a rossing head adjacent one end of a plurality of said rolls, the latter being constructed to rotate a log engaged thereby 95 while feeding it as described, guards for limiting the lateral movement imparted to a log by the feed rolls at one side of the rossing head, and means for automatically shifting said guards to permit a log to be discharged from the machine after passing the rossing head. 100

3. The combination in a debarking machine, of a suitable frame, a rossing head at one side of the frame, a series of feed rolls 105 adapted to feed a log longitudinally and laterally toward the side of the frame adjacent the rossing head, means for limiting the lateral movement of a log after passing the rossing head, and means for automatically moving said limiting means to inoperative position. 110

4. The combination in a debarking machine, of a suitable frame, a rossing head at one side of the frame, a series of feed rolls 115 adapted to feed a log longitudinally and laterally toward the side of the frame adjacent the rossing head, means for limiting the lateral movement of a log after passing the rossing head, and means adapted to be actuated by the longitudinal movement of a log 120 for moving said limiting means to inoperative position.

5. The combination in a debarking machine of a frame carrying a series of feed 125 rolls inclined as set forth, a portion of said rolls having end flanges, a rossing head arranged adjacent to the flanged rolls, guards arranged adjacent to the rolls without flanges and acting to limit the lateral move- 130

ment of a log, and means for shifting said guards out of position when a log passes beyond the flanged rolls whereby the log will be automatically discharged from the machine.

6. The combination in a debarking machine of a frame carrying a series of feed rolls inclined as set forth, a portion of said rolls having end flanges, a rossing head arranged adjacent to the flanged rolls, guards arranged adjacent to the rolls without flanges, to limit lateral movement of a log in the direction of the rossing head, and a contact device adapted to be engaged by the logs for shifting said guards out of position when a log passes beyond the flanged rolls to permit the logs to be automatically discharged.

7. The combination with the log support of a debarking apparatus, of a rotatable rossing head provided with spring teeth that are supported within and project laterally through slots in the head as set forth.

8. The within described rossing head having a hollow slotted cylinder, and yieldingly supported teeth extending through said slots.

9. A rossing head having a cylindrical body with slots therein, teeth projecting through said slots, and means for carrying each tooth with a spring pressure to one end of the slot through which it projects.

10. The combination in a rossing head of a slotted cylinder, a series of bars supported within the cylinder, and spring teeth each consisting of a strip of resilient metal coiled

about one of the bars and projecting 35 through one of the slots.

11. The combination in a rossing head of a slotted cylinder, a series of bars supported within the cylinder, and spring teeth each consisting of a strip of resilient metal coiled 40 about one of the bars and projecting at both ends through one of the slots, one of the ends projecting outward beyond the other.

12. The combination in a rossing head of a slotted cylinder, heads provided with bearings for a series of parallel rods, and teeth, each consisting of a strip of spring metal coiled about one of the bars and having a curved end projecting through one of the slots. 45 50

13. The combination in a rossing head of a slotted cylinder, heads provided with bearings for a series of parallel rods, and teeth each consisting of a strip of spring metal coiled about one of the bars and having a 55 curved end projecting through one of the slots, the other end also projecting through the slot and bent to engage the end of the said slot.

14. The combination with the rosser head of a spring tooth provided with teeth as set forth. 60

In testimony whereof I affix my signature in presence of two witnesses.
